UNITED STATES PATENT OFFICE

ABRAHAM P. LUBELL, OF NEW YORK, N. Y.

GARTER OR THE LIKE

Application filed September 15, 1931. Serial No. 562,397.

My invention relates to a garter, its object being to provide a novel and an improved device of this character for use by men, women and children, to prevent hose and stockings from slipping down on the leg. The device of my invention is also useful in other places and capacities, such for instance, as retaining a sleeve from slipping on the arm, or for maintaining a belt or other article 10 or portion of clothing in place.

An object of the invention is the provision of a garter construction which, while efficiently sustaining the stocking, will not bind or constrict the leg, and, therefore, will not 15 interfere with the free movement of the blood in the veins and capillaries.

Another object is to provide a construction which will be comfortable in use, will not irritate the skin by rubbing thereon, and 20 which will not pull or draw upon the flesh.

Another object of the invention is the provision of a garter which extends transversely or obliquely of the leg for a distance, but does not extend entirely around or encircle 25 the leg. The device is constructed for attachment to the stocking at opposite points, and between such points it includes an elastic or yieldable element, capable of ready expansion and contraction. With my improved 30 device, the stocking itself is, in effect, caused to serve as a part of the holding means by which to be sustained in place.

Another object of the invention is to provide 35 a garter construction of few parts, which will be exceedingly economical to manufacture, and one which can be applied to the stocking and removed therefrom with ease and dispatch.

With the above and other objects in view, the invention consists in the improved garter construction, and in the form, construction, and relative arrangement of its several parts, as will be hereinafter more fully described 45 and claimed.

In the drawing:—

Figure 1 represents a perspective view, showing a garter made in accordance with my invention and applied to a short stocking terminating below the knee; and

Fig. 2. represents a plan view of the garter detached from the stocking.

By referring to the drawing, it will be seen that the invention is disclosed as comprising an elongated elastic element in the form of a helical spring 10 adapted to be expanded and to automatically contract after each expansion. The opposite ends of the helical spring are shaped to form terminal loops 11. With each of these loops is pivotally engaged an 60 end piece or connector 12 carrying a fastening member 13.

Preferably as shown, the end pieces or connectors 12 may be produced from light wire, bent at one end to provide loops 14 in pivotal engagement with the terminal loops 11 of the spring, and at the opposite end to provide loops 15 in pivotal engagement with the eyes 16 of the fastening members 13. Between the loops 14 and 15, the wires are bent in opposite directions to produce angular portions 17. In this way, I provide an elongated garter or holder construction consisting of a central elastic element, at each end of which is pivotally connected an end piece or connector 12 with which in turn is pivotally connected a fastening member 13. In the present instance, the fastening members 13 are represented as comprising safety pins adapted readily to be engaged with the fabric or material of a stocking as shown at 18.

As represented in Fig. 1, the garter in use is preferably applied to the stocking just below the top edge 19 thereof. Application is made by connecting one of the safety pins to the stocking at one side of the leg and then extending the garter transversely of the leg and across the front portion thereof, so that the other safety pin can be attached to the stocking at the opposite side of the leg. Manifestly, before attaching the second safety pin to the stocking, the spring is expanded to the extent necessary to effect close fitting of the rear portion 20 of the stocking to the contour of the leg. Between the opposite points at which the safety pins are connected with the fabric of the stocking, the rear portion 20 of the stocking constitutes, in effect, a continuation of the garter device, so that the stocking is firmly maintained on the

leg to prevent downward slipping thereof. The helical spring is composed of relatively light material, readily capable of bending longitudinally in a curve in conformity with the curvature of the leg. The end pieces or connectors 12 are so bent or twisted that they will come flatwise against the leg in conjunction with the loops to which they are connected, as shown in Fig. 1. It will be obvious that the sides of the wire end pieces or connectors are bent in opposite directions to form a base having a lateral breadth sufficient to prevent any turning of the garter structure upon the leg of the wearer. By pivotally connecting the end pieces between the helical spring and the safety pins, the safety pins may be freely swung or manipulated in order readily to attach them to the stocking as well as to disconnect them therefrom. While I prefer to provide the end pieces 12 between the elastic element and the fastening members, it will be recognized that, if desired, the fastening members may be pivotally connected directly to the terminals of the elastic element.

Although for the purpose of demonstrating its practicability, I have in Fig. 1 illustrated my garter or holder as applied to a short stocking 18 terminating below the knee, it will be readily recognized that my garter or holder may with equal facility and advantage be applied above the knee to a long stocking reaching above the knee. Over the ring-shaped garter so frequently used by women, girls, and boys for sustaining a long stocking above the knee, the garter of my invention is a great improvement, since it does not indent or constrict the flesh so as to cause irritation or to restrict the circulation of the blood. For the same reasons, it is found to be a great improvement over the leg-encircling garters used by men below the knee for holding short stockings or socks.

As intimated in the statement of objects, the garter of my invention may be used on a sleeve to sustain it in the position desired; and it may further be employed as a fabric holder in any place or capacity where it is desired to sustain a fabric or a portion of a garment by tensioning the same to effect close fitting to a firm or relatively firm contour. Although I have illustrated the garter as applied transversely of the leg, it will be recognized that it may, if desired, be applied in an oblique direction.

In the present embodiment, my invention has been illustrated in its simplest form and without any covering. If desired, the spring, end pieces and even parts of the fastening members may be covered with fabric or even rubber material. Although, in the present embodiment, ordinary safety pins are used for fastening members, it is to be understood that in place of safety pins, any suitable or approved fastening members or even clasps

of the type commonly used on garters for clasping the material of the stocking may be employed. In place of the helical spring, an elastic rubber element may be used.

From the foregoing description taken in connection with the accompanying drawing, it will be seen that I have provided a very simple, practical, an efficient garter, which is composed of few parts and may be manufactured and sold at low cost.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

I claim:—

1. A stocking garter adapted to conform to the rotundity of the leg to constrict the stocking around the leg, comprising end fasteners adapted to be engaged with the stocking by penetrating the weave thereof, a coiled spring having capacity for expansion and contraction, and connectors connecting the fasteners respectively with the opposite ends of the spring, comprising wire frames the sides of which are bent in opposite directions to form a base of sufficient lateral extent to prevent turning of the garter on the leg.

2. A stocking garter adapted to conform to the rotundity of the leg to constrict the stocking around the leg, comprising end fasteners adapted to be engaged with the stocking by penetrating the weave thereof, a coiled spring having capacity for expansion and contraction, and means connecting the fasteners with the coiled spring, comprising wire frames having sides spread in opposite directions to form a base of sufficient lateral extent to prevent turning of the garter on the leg, said wire frames being pivotally connected at their outer ends with the fasteners and at their inner ends with the ends of the spring.

In testimony that I claim the foregoing as my invention, I have signed my name hereto.

ABRAHAM P. LUBELL.
